US00D798436S

(12) **United States Design Patent** (10) **Patent No.:** **US D798,436 S**
(45) **Date of Patent:** **** Sep. 26, 2017**

(54) **EARPLUG HANDLE**

- (71) Applicant: **Honeywell International Inc.**, Morristown, NJ (US)
- (72) Inventors: **Rocky Qu**, Shanghai (CN); **Zhao Xia Jin**, Shanghai (CN); **Jex Zhang**, Shanghai (CN); **Charlotte Loomis**, La Jolla, CA (US); **Dave Mulvey**, San Diego, CA (US)
- (73) Assignee: **Honeywell International Inc.**, Morris Plains, NJ (US)
- (**) Term: **14 Years**

(21) Appl. No.: **29/519,541**

(22) Filed: **Mar. 5, 2015**

(51) LOC (10) Cl. **24-04**
(52) U.S. Cl. **USPC D24/106**

(57) **CLAIM**

The ornamental design for a earplug handle, as shown and described.

DESCRIPTION

FIG. 1 is a top perspective view of an earplug handle in accordance with the new design;

FIG. 2 is a bottom perspective view thereof;

FIG. 3 is a aside elevation view thereof;

FIG. 4 is a side elevation view thereof, for the side opposite that of FIG. 3;

FIG. 5 is a side elevation view thereof, for the side 90 degrees from that of FIG. 4;

FIG. 6 is a side elevation view thereof, for the side opposite that of FIG. 5;

FIG. 7 is a top elevation view thereof; and,

FIG. 8 is a bottom elevation view thereof.

The broken lines shown in the drawings are only provided to illustrate the environment of the design, and form no part of the claimed design.

1 Claim, 4 Drawing Sheets
